CLAIM

The ornamental design for a cantilevered snap fit case, as shown and described.

DESCRIPTION

FIG. 1 is a front perspective view of a cantilevered snap fit case;

FIG. 2 is a back perspective view of the cantilevered snap fit case of FIG. 1;

FIG. 3 is a front view of the cantilevered snap fit case of FIG. 1;

FIG. 4 is a back view of the cantilevered snap fit case of FIG. 1;

FIG. 5 is a left view of the cantilevered snap fit case;

FIG. 6 is a right view of the cantilevered snap fit case of FIG. 1;

FIG. 7 is a top view of the cantilevered snap fit case of FIG. 1; and,

FIG. 8 is a bottom view of the cantilevered snap fit case of FIG. 1.
